HOLDER FOR A FISHING ROD

Llewellyn H. Wise, Ashland, Ky.

Application January 3, 1956, Serial No. 39,583

Term of patent 14 years

(Cl. D31—4)

Fig. 1.

Fig. 2.

Fig. 3.

Fig. 4.

Fig. 5.

Fig. 1 is a view in front elevation of a holder for a fishing rod, showing my new design;

Fig. 2 is a top plan view of the holder for a fishing rod;

Fig. 3 is a bottom plan view thereof;

Fig. 4 is a view in end elevation thereof; and

Fig. 5 is another view in end elevation thereof showing the opposite end.

The fishing rod and stick for supporting the holder are shown in dot-dash lines for illustrative purposes only.

I claim:

The ornamental design for a holder for a fishing rod, as shown and described.
